WILLIAM F. COTTER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

AUTOMATICALLY-OPERATED PICK-UP SWITCH

Application filed September 11, 1928. Serial No. 305,289.

This invention relates to systems for amplifying sound, and more particularly to systems for the amplification of phonographicaly recorded sounds through thermionic or 5 electronic means.

A practical object of this invention is to provide means for automatically connecting an electromagnetic or phonographic pickup or circuit to the audio-frequency amplifier 10 of a radio receiver, said means being preferably adapted to simultaneously disconnect the amplifier from the detector when said pickup is connected to said amplifier. The purpose of disconnecting the amplifier from 15 the detector is to prevent static and electrostatic noises, as well as harmonics and heterodyne squeals and whistles, from passing into the amplifier when the pickup is in operation.

The said means comprises, preferably, a 20 switch which is operated automatically when one of the members of the tuning means of said receiver (the condenser drive wheel or drum, for example) is rotated or moved beyond the tuning range, or at any predetermined point in its rotation.

In the event the tuning means are variable inductances then the moving parts of said inductances may be employed to operate said switch.

The invention is, of course, broader in scope than the example here cited, since the invention has application in many other ways which are within the principle thereof.

The invention is, broadly, the combination 35 with a movable tuning member of a switch adapted to be operated at a predetermined point in the movement of said member, whether said switch is operated to connect a pickup, connect or disconnect other circuits, or combinations of said operations.

The accompanying drawing, therefore, illustrates one of the many possible embodiments of my invention.

Fig. 1 is a circuit diagram of a radio receiving circuit having a switch automatically operable by the movable or tuning member of a condenser; Fig. 2 is similar to Fig. 1 showing the switch closed; Fig. 3 is a modification of Fig. 1 wherein is substituted 50 a single pole double throw switch for the

single pole throw switch of Figs. 1 and 2; Fig. 4 is a top view of a rotatable drum with which is associated the switch of Fig. 3; and Fig. 5 is a side view thereof.

Referring to Fig. 1, there is shown part of 55 a radio receiving and amplifying circuit. In order to connect the electromagnetic or phonographic pickup 1 to the audio frequency amplifier 2 of the receiver, there is provided a single pole single throw switch 60 3 or a single pole double throw switch 13, which is disposed adjacent the drum 4 (Fig. 4) mounted on the shaft 5 of a condenser 6. Attached to the side of the drum is an insulating strip or lug 7 over which is adapted 65 to open or close switch 3 as the case may be. The said strip 7 is placed on said drum at such a point that at a predetermined point in its rotation it shall operate said switch; preferably said strip is placed on said drum beyond the tuning range, say below zero, to 70 close said switch when the drum is rotated beyond said range.

In said circuit the switch has the arm 8 connected to the plate 9 of the detector tube 75 10—and to one of the pick-up terminals 12, 12, and the other arm 11 of said switch is connected to the other terminal 12, which may be grounded. The electromagnetic pickup 1 is adapted to be connected to said terminals 80 and hence to the amplifier 2.

It will be observed that in the arrangement shown in Fig. 1, the switch is so arranged 85 that the pickup circuit to the amplifier is normally disconnected and the detector is always connected to the amplifier, but the switch may be arranged as shown in (Fig. 2). It is not desirable when employing the pickup to have the radio frequency side of the receiver connected to the audio amplifier since to do so 90 introduces into the reproduction static and other interfering noises. I prefer therefore to disconnect the plate of the detector from the amplifier when the pickup is in operation, in substantially the same manner above described. That is, instead of the switch being normally open, it is normally closed (for 95 radio operation, Fig. 2), and when it is desired to use the pickup to arrange to have the lug 7 on the drum to open said switch so as to 100

disconnect the detector and since in this case (Fig. 2) the pickup circuit is always connected, the pickup will, of course, be connected.

It will be understood that, in the case of Fig. 2, when the receiver is in operation, the pickup is disconnected from the switch. The reason for this is that the low impedance of the pickup unit shunts the audio frequency system with the result that the energy from the detector is by-passed to ground.

The switch is therefore arranged to be opened when the drum is turned below zero or beyond the tuning range of the condenser so as to disconnect the detector circuit from the amplifier, the amplifier being permanently connected to the pickup circuit as shown in Fig. 2.

Instead of employing a single pole single throw switch as above indicated, I may use a single pole double throw switch 13 shown in Fig. 3. Said switch 13 is provided with two stationary contacts 14 and 15 and a movable contact arm 16.

The arm 14 is connected to the plate 9 of the detector, while the other stationary contact 15 is connected to the pickup. The movable arm 16 is connected to the primary 18 of the first audio frequency transformer 19 of the thermionic amplifier.

By this arrangement either the plate or the pickup may be arbitrarily connected to the amplifier, but said switch is operated in substantially the same manner as the others.

Having thus described my invention, what I claim is:

1. The combination with a radio receiver having a tunable circuit connected to an audio-frequency amplifying circuit, of a phonograph pickup circuit, and a switch arranged to be operated by the tuning means to disconnect said tunable circuit from said amplifier and connect said pickup to said amplifier.

2. The combination with a radio receiver having tuning means and an audio-frequency amplifier, of a phonograph pickup circuit, and a switch operable by said tuning means to connect said pickup circuit to said amplifier.

3. The combination with a radio receiver having tuning means, a detector and an audio-frequency amplifier, of a phonograph pickup circuit, and a switch in the plate circuit of the detector operable by said tuning means to connect said pickup circuit to and disconnect said detector from said amplifier.

4. The combination with a radio receiver having a tunable circuit, tuning means therefor, and an audio-frequency amplifier, of a phonograph pickup, and a switch arranged to be operated by said tuning means to connect said pickup to said amplifier when said tuning means is moved beyond the tuning range.

5. The combination with a radio receiver

having a tunable circuit, tuning means and an audio-frequency amplifier, of a phonograph pickup, and a switch arranged to be operated by said tuning means when said means is moved beyond the tuning range, to disconnect said tunable circuit from the audio-frequency amplifier and to connect said pickup to said amplifier.

6. The combination with a radio receiver having tuning means and an audio-frequency amplifier, of a phonograph pickup circuit, and a switch operable by said tuning means to connect said pickup circuit to said amplifier when said tuning means is moved beyond the tuning range.

7. The combination with a radio receiver having tuning means, a detector and an audio-frequency amplifier, of a phonograph pickup circuit, and a switch in the plate circuit of the detector operable by said tuning means to connect said pickup circuit to and disconnect said detector from said amplifier, when said tuning means is moved beyond the tuning range.

8. The combination with a phonograph pickup circuit, of a thermionic amplifier circuit, a switch between said pickup and amplifier circuits, a tuned circuit, a rotatable tuning member, and means thereon adapted to operate said switch when said member is moved beyond the tuning range.

9. The combination with a phonograph pickup circuit, of a thermionic amplifier circuit, a switch connecting the pickup circuit to the amplifier circuit, radio-frequency and detector circuits, a rotatable tuning member, and means thereon adapted to operate said switch, when said member is moved beyond the tuning range, to disconnect the radio-frequency and detector circuits from and connect the pickup circuit to the amplifier circuit.

10. The combination with a radio receiver having radio-frequency, detector and amplifier circuits, of a rotatable tuning member, a switch, a phonograph pickup circuit, and means on said member adapted to operate said switch when said member is moved beyond the tuning range, to disconnect the radio-frequency and detector circuits from and connect the pickup circuit to the amplifier circuit.

11. The combination with a radio receiver having rotatable tuning means, a tuned detector circuit and an audio-frequency amplifier, of a phonograph pickup circuit, and a switch in the plate circuit of the detector operable by means on said tuning means, when said tuning means is moved beyond the tuning range, to disconnect the tuned circuit from and connect the pickup circuit to the amplifier.

In testimony whereof I affix my signature.
